UNITED STATES PATENT OFFICE.

ALBERT E. STOKER, OF DALLAS, TEXAS.

CARBURETER.

No. 873,392.

Specification of Letters Patent.

Patented Dec. 10, 1907.

Application filed February 7, 1907. Serial No. 356,204.

To all whom it may concern:

Be it known that I, ALBERT E. STOKER, a citizen of the United States, residing at Dallas, in the county of Dallas and State of 5 Texas, have invented certain new and useful Improvements in Carbureters, of which the following is a specification.

My invention relates to improvements in carbureters, and relates more particularly to 10 that style of manually-operated carbureter designed for use on automobile gas-engines, although I do not confine myself to this specific use but reserve the right to apply it to any purpose for which it is adapted.

15 The invention consists in the novel construction, combination and arrangement of parts hereinafter described, pointed out in the claims, and illustrated in the accompanying drawing, in which:—

20 Figure 1 represents a front elevation of the carbureter. Fig. 2 shows a side elevation of the same. Fig. 3 is a vertical central section on line III—III of Fig. 2. Fig. 4 is a broken vertical section on line IV—IV of Fig. 1.

25 In carrying out the invention I employ a globular casing 1 open at its top 2 for the admission of air and provided with a flange 3 at its discharge end, whereby it may be readily secured to the gas-engine (not shown.)

30 4 designates a disk-valve arranged in the discharge end of the casing upon a shaft 5, projecting through one end of said casing, and provided with a crank 6 adjustably secured thereto by a set-screw 7.

35 8 designates a circular spreader centrally-disposed in a mixing-chamber 9 within the enlarged portion of the casing. Said spreader has a concaved upper surface 10 for retaining the hydrocarbon oil as it drops thereon 40 until said oil evaporates. Said spreader is hollow and connected to the lower portion of the casing by a tubular stem 11 through which a pipe 12 extends, said pipe being, preferably, connected with the exhaust pipe

45 of the engine, so that heat may be introduced into the chambered spreader and thus hasten the process of vaporizing the oil as it drops upon said spreader. The vaporization of the oil is further hastened by the introduction of air through opening 2 and directed against the spreader by an inverted frusto-conical flange 13 integral with the casing.

50 14 designates an oil supply pipe secured to the top of casing 1 and communicating

with a vertical chamber 15, provided at its 55 upper portion with a stuffing-box 16 and at its lower tapered end with a nozzle 17 having a valve-seat 18 centrally-disposed above the spreader 8.

19 designates a needle-valve extending 60 through chamber 15 for controlling the flow of oil. The upper threaded end 20 of the needle-valve is adjustably engaged by a nut 21 to which a lever 22 is pivotally secured by screws 23. Said nut is reliably locked in position by a clamping-nut 24. Lever 22 is fulcrumed upon the upper end of an arm 22^a projecting from chamber 15.

25 designates a bell-crank lever connected to lever 22 by a link 26. Each of said levers 70 has a series of holes 27, 28 for the adjustable reception of link 26 and whereby the movement of the needle-valve is adjusted, for instance, by placing the ends of the link through the holes nearest the fulcrumed points of the 75 levers, it is obvious that the needle-valve will be raised but a short distance above its seat and permit but a small amount of gasolene to discharge from the nozzle, whereas if said link is adjusted to the outermost holes the needle- 80 valve will be raised sufficiently to permit the maximum amount of oil to discharge from the nozzle. Valve 4 is simultaneously opened with the needle-valve to permit the mixture to be drawn into the engine by a link 29 piv- 85 otally secured at its ends to crank 6 and one end of lever 25. The upper arm of lever 25 has an eye 30 for the reception of a connect- 90 ing-rod or other device employed in actuating the lever. By employing the above 95 connections it is obvious that the strokes of the needle-valve may be varied to admit more or less oil without checking the action of valve 4 which is always opened to the widest point so that the mixture will have free in- 95 gress to the cylinder.

31 designates a drain leading from the discharge end 3, for the escape of any oil which may accumulate therein.

From the above description it is obvious 100 that I have produced a carbureter which is of simple and compact construction, and thoroughly adapted for the purpose intended.

Having thus described my invention, what I claim is:—

105 A carbureter consisting of a mixing-chamber, an oil inlet pipe opening into said chamber, a hollow spreader within the chamber

having a concave face upon which the oil drops, a tubular stem supporting said spreader and communicating with a source of heat, a valve in the oil inlet pipe, a passage 5 connecting the mixing chamber and engine, a valve adapted to close said passage, and means connecting the valves so they will be simultaneously operated, said means being

adjustably connected to the valve in the oil inlet, for the purpose described. 10

In testimony whereof I affix my signature, in the presence of two witnesses.

ALBERT E. STOKER.
